(57) **CLAIM**

The ornamental design for a trigger sprayer, as shown and described.

DESCRIPTION

FIG. 1 is a perspective view of the trigger sprayer.

FIG. 2 is a second perspective view of the trigger sprayer.

FIG. 3 is a front view of the trigger sprayer.

FIG. 4 is a right side elevational view of the trigger sprayer.

FIG. 5 is a rear view of the trigger sprayer.

FIG. 6 is a left side elevational view of the trigger sprayer.

FIG. 7 is a top view of the trigger sprayer; and,

FIG. 8 is a bottom view of the trigger sprayer.

The uniformly dashed broken line portions of the disclosure are for illustrative purposes only and form no part of the claimed design.

1 Claim, 4 Drawing Sheets

FIG. 3

FIG. 4

FIG. 5

FIG. 6

FIG. 7

FIG. 8
